UNITED STATES PATENT OFFICE.

THURE E. DAHL, OF NEW YORK, N. Y.

DESIGN FOR A CHANDELIER.

Application filed July 21, 1921. Serial No. 486,576. Term of patent 3½ years.

To all whom it may concern:

Be it known that I, THURE E. DAHL, a subject of the King of Sweden, and resident of New York, in the county of New York and State of New York, have invented a new and ornamental Design for a Chandelier, of which the following is a specification, reference being had to the accompanying drawings, forming part thereof.

The figure is a perspective view of a chandelier, showing my new design.

I claim:

The ornamental design for a chandelier, as shown.

THURE E. DAHL.
